US00D889326S

(12) **United States Design Patent** (10) Patent No.: **US D889,326 S**
(45) Date of Patent: ** Jul. 7, 2020

(54) **CAR BUMPER**

(71) Applicant: **FERRARI S.P.A.**, Modena (IT)

(72) Inventor: **Flavio Manzoni**, Maranello (IT)

(73) Assignee: **FERRARI S.P.A.**, Modena (IT)

(**) Term: **15 Years**

(21) Appl. No.: **35/506,306**

(22) Filed: **Jul. 18, 2018**

(80) **Hague Agreement Data**

Int. Filing Date: **Jul. 18, 2018**

Int. Reg. No.: **DM/103181**

Int. Reg. Date: **Jul. 18, 2018**

Int. Reg. Pub. Date: **Jan. 18, 2019**

(30) **Foreign Application Priority Data**

Jan. 19, 2018 (EM) 004672921

(51) **LOC (12) Cl.** **12-16**

(52) **U.S. Cl.**

USPC **D12/163**

(58) **Field of Classification Search**

USPC D12/88, 92, 211, 209, 181, 173, 163
